RECEPTACLE FOR COMBS AND FILES

Frank E. Wakefield, North Attleboro, Mass., assignor to Evans Case Company, North Attleboro, Mass., a corporation of Massachusetts

Application October 8, 1937, Serial No. 163,101

4 Claims. (Cl. 132—79)

The invention relates to a simple, compact and attractive case for carrying together a comb and a file. The device is especially adapted for use in the pocket or hand bag or pocket book, 5 or any other situation in which it is desirable to have together these toilet articles.

In general the invention consists of a casing or covering surrounding substantially all of the comb and protecting it from injury and dirt. 10 Associated with this is a casing or covering for a file which is received and held in such a way as to be protected from injury or dirt. Both comb and file are so covered that they will not readily catch in adjacent materials and the case itself 15 is preferably free from any obstructive projecting portion which will catch in, or interfere with, adjacent materials or articles.

In one aspect of the invention a portion of the structure forming the casing or sheath for the 20 file may assist in retaining the comb in position in its portion of the case.

In the accompanying drawing a specific preferred form of the device is illustrated. Fig. 1 is a plan view of a blank from which a comb case is made. Fig. 2 is a perspective view of a 25 formed portion of the sheath for the file. Fig. 3 is a side elevation of the assembled device illustrating both comb and file in place. Fig. 4 is a transverse vertical section on the line 4—4 of 30 Fig. 3.

The comb A is illustrated as provided with a finger member 10 which is shown as being bent over and extending slightly down both sides of the upper part of the comb at about its central portion, although it might be placed at any other point on the back of the comb. The sides of the finger member 10 are not impressed into the comb but lie along its sides and stand out therefrom. The finger member 10 may be held in 40 position on the comb in any suitable manner. Pins 11 are illustrated for this purpose and are shown as extending through the top of the finger piece and into the back of the comb. The comb so fitted may be placed into a casing member 45 which may be made from the blank illustrated in Fig. 1. This may consist of a sheet of metal or other material which may be bent along lines at its center so that the portion shown at the top of Fig. 1 forms the front 12 of the comb case. 50 The portion 13 shown at the bottom of Fig. 1 forms the back of the comb case and the intermediate portion 14 forms the bottom of the comb case. At a proper point on the outer edge of the members 12 and 13 or of at least one of them 55 may be provided a recess 15 which corresponds

in shape and size with the downward depending side member of the finger piece 10 so that when the comb is placed in its pocket as indicated in Figs. 3 and 4 the finger piece 10 forms means for positioning the comb in the pocket and by projecting into the recess 15 tends to position the comb in the case and prevent its moving longitudinally of the case. At the same time this finger piece is free to be grasped to remove the comb from the case. 5

The blank illustrated in Fig. 1 is provided with suitably positioned openings 16 through which may project lugs 17 formed and correspondingly positioned at the bottoms or inner edges of the side rims 18 of the file sheath or casing member 19 which is illustrated in Fig. 2. When this casing member 19 is placed in position as illustrated in Figs. 3 and 4 on the outside of the front member 12 of the comb casing the lugs 17 will project through the opening 16 and into the interior of the comb receptacle. The lugs 17 may now be turned over against the inner face of the front wall member 12 to retain the sheathing member 19 in position and with the depending side wall members 18 in contact with the wall 12. The sheathing member 19 may be formed to correspond in shape with the end of the file member B and the height of the wall members 18 or the size of the sheath or both is such that when the file B is placed in the sheath 19 it may be retained therein by friction. The size of the sheath member 19 is not material but it is found sufficient to have the sheath large enough to merely cover the rough or abrasive portion of the file B leaving the smooth handle portion projecting and free to be grasped for removing the file from the casing. The members 12 and 13 may be so positioned with respect to each other that they may produce a friction grasp upon the comb when it is centered in the position. The overturned lugs 17 against the inner side of the wall 12 may be engaged by the comb and increase the frictional holding effect or it may be that as the comb is inserted in the casing the lugs 17 will extend between teeth in the comb and so tend to aid in keeping the comb from falling out of the device or moving endwise in it. This arrangement makes it possible to have the comb pocket consist of front and back walls 12 and 13 joined by the unitary bottom member 14 leaving the top and sides open so that the receptacle may tend to continuously keep itself clean by failing to retain dirt. 35 40 45 50 55

The invention is not confined to the specific embodiment illustrated which may be altered or 55

varied in many respects and still exemplify the invention. The material of which the device is manufactured is not involved in the invention. The device may be ornamented by enamelling, 5 chasing, plating, surface ornamentation or in any other suitable or desired manner.

I claim as my invention:

1. A casing for a comb having projecting finger pieces comprising a receptacle having open 10 ends and open top and consisting of two side members and a unitary connecting bottom member, the side members being each substantially the same in area as the comb, notches at the top edges of the side members to receive projecting 15 finger pieces on the comb, and a sheath for a nail file consisting of a portion of the outer surface of one side member and an overlying member having a portion shaped to cover only the roughened portion of the file, and an inwardly 20 extending border provided with inwardly projecting lugs which extend through the side member and are bent over within the receptacle so as to be engaged by the comb and cause it to normally remain in its receptacle.
- 25 2. A casing for a comb having projecting finger pieces consisting of two side members and a unitary connecting bottom member, notches at the top edges of the side members to receive projecting finger pieces on the comb, and a sheath

for a nail file consisting of a portion of the outer surface of one side member and an overlying member having a portion shaped to cover the roughened portion of the file and an inwardly extending border provided with inwardly projecting lugs which extend through the side member and are bent over within the comb receptacle. 5

3. A casing for a comb comprising two side members and a connecting bottom member, a 10 sheath for a nail file consisting of a portion of the outer surface of one side member and an overlying member having a portion shaped to cover the file and provided with inwardly projecting lugs which extend through the side member 15 and are bent over within the receptacle so as to be engaged by the comb to cause it to normally remain in its receptacle.

4. A casing for a comb comprising two side members and a unitary connecting bottom member, a sheath for a nail file consisting of a portion of the outer surface of one side member and an overlying member provided with inwardly projecting lugs which extend through the side member 20 and are bent over within the receptacle 25 so as to be engaged by the comb to cause it to normally remain in its receptacle.

FRANK E. WAKEFIELD.
